UNITED STATES PATENT OFFICE.

EMIL J. F. QUIRIN, OF TIOGA CENTRE, NEW YORK.

CAR BRAKE AND STARTER.

SPECIFICATION forming part of Letters Patent No. 374,084, dated November 29, 1887.

Application filed July 19, 1887. Serial No. 244,702. (No model.)

To all whom it may concern:

Be it known that I, EMIL J. F. QUIRIN, a citizen of the United States, and a resident of Tioga Centre, in the county of Tioga and State 5 of New York, have invented certain new and useful Improvements in Combined Car Brake and Starter; and I do hereby declare that the following is a full, clear, and exact description of the invention, which will enable others skilled 10 in the art to which it appertains to make and use the same, reference being had to the accompanying drawings, which form a part of this specification, and in which—

Figure 1 is a top plan view of the bottom 15 frame of a tram-car provided with my improved brake and starter. Fig. 2 is a bottom view of the same. Fig. 3 is a longitudinal vertical sectional view on line xx , Figs. 1 and 20 2, being inside of the wheels at one side; and Fig. 4 is a perspective view of the mechanism at one end of the car, showing the frame-work 25 of the bottom of the car in dotted lines and showing parts of the wheels broken away.

Similar numerals of reference indicate corresponding parts in all the figures.

My invention has relation to that class of car-starters used in tram-cars or street-cars in which the power of the team pulling on the draw-head in starting is conveyed to the wheels, 30 turning them, thus rendering the starting easier than the dead straight pull upon the car; and it consists in the improved construction and combination of parts of such a starter in which the brakes which serve to stop the 35 revolutions of the wheels are mounted upon pivoted arms which will bring the brake-shoes in contact with the wheels and stop their revolutions, and at the same time when operated from the draw-bars will carry the brake-shoes 40 upward and forward, starting the wheels, as hereinafter more fully described and claimed.

In the accompanying drawings, the numerals 1 indicate the side sills of the bottom frame or platform of the car, and the ends of these 45 sills are connected by the end pieces, 2, and by cross-pieces 3 and 4, forming supports for the dash and the end platforms of the car. The sills are provided with suitable brackets and boxes, 5, for the ends of the axles 6 of the 50 wheels 7, all of which parts are of the usual construction.

The draw-heads 8 may be of any suitable construction, and are secured to or form parts of the draw-bars 9, which slide longitudinally in bearings 10 upon the under sides of the 55 cross-pieces and end pieces, and these draw-bars have coiled springs 11 wrapped around them and bearing against the outer cross-pieces and against pins or bolts 12, inserted through the draw-bars at the outsides of the 60 bearings in the inner cross-pieces, the springs serving to return the draw-bars into their normal inwardly-drawn positions.

The upper side of the forward portion of each draw-bar is provided with a notch, 13, 65 having a forwardly-facing shoulder, and dogs 14 are pivoted upon the inner sides of the end pieces and may engage the said notches when allowed to drop downward, the said dogs having upwardly-projecting arms 15, which 70 may be engaged by slides 16, sliding in vertical slots or ways 17 in the dash-boards of the platforms, holding the dogs raised out of engagement with the notches.

A rock-shaft, 18, is journaled in suitable 75 transverse bearings, 19, under the inner cross-piece at each end of the car, and this shaft is provided at its middle with a downwardly-projecting arm, 20, to the end of which a bar, 21, is pivoted, having its forward or outer 80 arm pivoted to the draw-head, and the ends of the shaft have downwardly-projecting arms 22 secured to them.

Sleeves or collars 23 are journaled upon the axles immediately inside of the wheels, bearing with their ends against the wheels and against suitable stops, 24, upon the axles, and arms 25 project radiating from the ends of these collars, having rods 26 pivoted to their outer ends and to the ends of the arms upon 85 the ends of the rock-shaft, the said arms projecting normally upward. The forward or outer sides of the inner ends of these arms at the collars are provided with eccentrically-projecting cams 27, which bear against pins or 90 studs 28, projecting inward from the short arms of levers 29; pivoted and sliding with longitudinal slots 30 upon the axles between the collars and the wheels, the outer ends of the long arms of these levers having the brake-shoes 31 secured upon them and projecting 95 normally toward the middle of the car.

Chains 32 are secured to the sills and to the ends of the long arms of the levers, preventing the arms and shoes from falling to the ground or rail. The inner sides of the long arms of the levers are provided with inwardly-projecting perforated ears or lugs 33, in which slide rods 34, having shoes 35 upon their inner ends bearing against the collars, and having coiled springs 36 bearing against the shoes and against the inner ears, forcing the said shoes against the collars.

Levers 37 are fulcrumed to rock in a horizontal plane upon brackets or arms 38, projecting inward from the inner sides of the inner cross-pieces, and the inner ends of these levers have downwardly-projecting lips 39, with which they bear against the inner ends of the draw-bars, while brake-rods 40 or chains are attached to the outer ends of the longer arms of the levers and pass to the brake-shafts 41 at the ends of the ears, having chains 42 at the ends which wind upon the brake-shafts, the said brake-shafts having suitable handles, 43, and ratchet-wheels 44, engaged by the usual pawls, 45.

When the car is normally running, the dogs at the ends of the platforms are supported in their raised positions by the slides holding the upwardly-projecting arms allowing the draw-bars to be drawn freely out, the dog at the end having the team attached to it, however, being let down when the car has been started, so that the dog may engage the notch of the draw-bar when the pull has ceased and the spring of the draw-bar has drawn it in. When it now is desired to stop the car, the brake-shaft is turned in the usual manner, winding the chain and drawing the outer end of the lever at the opposite end inward, forcing the end having the lip against the inner end of the draw-bar at that end, forcing the draw-bar out. This will cause the draw-bar to draw outward upon the bar pivoted to it, drawing the arm of the rock-shaft outward and tilting the arms at the ends of the shaft outward, which will again in their turn tilt the arms of the collars outward, causing their cams to draw the levers inward and bringing the brake-shoes to bear against the wheels, the arms gradually drawing the arms so far outward that they will carry the levers and brake-shoes with them and reverse the motion of the wheels, effectually stopping the car.

When it now is desired to again start the car, the dog at the end at which the team is raised, which may be done by a kick of the foot by the driver, whereupon the brake is released and the team started. This will cause the team to draw out the draw-bar at that end, rocking the shaft and bringing the brake-shoes at that end in contact with the wheels and tilting the levers upward and forward, causing them to carry the wheels with them, so that the car will be effectually started, the wheels revolving freely under the brake-shoes when the latter are raised to the highest position. When, now, the car has been started

sufficiently to run freely, the spring of the draw-bar will draw it in, and the springs upon the rods having the shoes bearing against the collars will force the brake-shoes from contact with the wheels, sliding the levers outward with the slots, so that the shoes will again occupy their normal positions and be ready for again operating upon the wheels.

It will be seen that in stopping the car the wheels which at that time are the rear wheels will be revolved in the opposite direction to which they revolve when traveling forward, so that the car will be most effectually stopped, and so that the tendency of the wheels to revolve in one direction will force the brake-shoes so much harder against them, and it will also be seen that the team will exert a much more advantageous pull upon the wheels starting their revolutions than if simply pulling against the car in a straight line. It will also be seen that if the team makes false starts or jumps, as is often the case, every start will bring the car forward, bringing the car against the team and preventing its stalling or balking, the device doing away with the dead-pull, which is liable to make car-horses balky, as they do not feel any effect of their starts and simply pull against a dead object, and curing their balkiness by forcing the car forward upon them when they have jumped forward and fall back. In this manner the device will save the live stock by enabling it to exert the greatest power with the slightest exertion, and will at the same time prevent the forming of bad habits of the stock.

Having thus described my invention, I claim and desire to secure by Letters Patent of the United States—

1. In a car-starter, the combination of a sleeve journaled upon the axle of the wheels and provided with a radiating arm having a cam projecting forward at its inner end, a lever, 29, sliding with a longitudinal slot upon the axle between the end of the sleeve and the wheel and having a stud, 28, upon its inner short arm bearing against the cam 27, and having a shoe, 31, at its outer end for clamping the periphery of the wheel, and provided with a spring, 36, for sliding it outward upon the axle, and a sliding draw-bar, 9, suitably connected to the arm of the sleeve, as and for the purpose shown and set forth.

2. In a car-starter, the combination of a sleeve journaled upon the axle of the wheels and provided with a radiating arm having a cam projecting forward from its inner end, a lever sliding with a longitudinal slot upon the axle between the end of the sleeve and the wheel and having a stud upon its short arm bearing against the cam, and having a shoe upon the outer end of its long rearwardly-projecting arm for clamping the periphery of the wheel, and provided with means for sliding it back upon the axle, a longitudinally-sliding draw-bar having a spring forcing it forward and a notch, 13, in its upper side, a dog, 15, engaging the notch, and a rock-shaft having

an arm at its middle connected by a rod to the sliding draw-bar and having an arm at its end pivotally connected by a rod to the arm of the sleeve, as and for the purpose shown 5 and set forth.

3. In a car-starter, the combination of a sleeve journaled upon the axle of the wheels and provided with an upwardly-radiating arm formed with a cam projecting forward from the inner end, a lever sliding with a longitudinal slot upon the axle between the sleeve and the wheel and provided upon its short arm with a stud bearing against the cam and at the end of its rearwardly-projecting long 15 arm with a shoe for clamping the periphery of the wheel, and having a chain, 32, secured to it and to the body of the car, a rod, 34, sliding in bearings upon the inner side of the lever and having a shoe, 35, at its inner end 20 bearing against the sleeve, and a spring, 36, forcing it inward, and a longitudinally-sliding draw-head suitably connected to the arm of the sleeve, as and for the purpose shown and set forth.

25 4. In a car-starter, the combination of a sleeve journaled upon the axle of the wheels and provided with an upwardly-radiating arm formed with a cam projecting forward from its inner end, a lever sliding with a longitudinal slot upon the axle between the sleeve and the wheel and provided upon its short arm with a stud bearing against the cam and at the end of its rearwardly-projecting long 30 arm with a brake-shoe supported by a chain 35 attached to the body of the car, a rod sliding in bearings upon the inner side of the lever and having a spring forcing it toward the sleeve, and having a shoe at its inner end bearing against the sleeve, a longitudinally-sliding 40 draw-bar provided with a spring to force it back and with a notch in its upper side, a dog engaging the notch and having an upwardly-projecting arm, a slide, 16, in the dash for engaging the upwardly-projecting arm 15, and a

rock-shaft having a central arm pivotally connected by a rod to the sliding draw-bar and having an arm at its end pivotally connected by a rod to the upwardly-projecting arm of the sleeve, as and for the purpose shown and set forth. 45

5. In a combined car brake and starter, the combination of sleeves journaled upon the axles of the wheels and having upwardly-projecting radiating arms provided with forwardly-extending cams at the inner ends, levers sliding upon the axles between the sleeves and the wheels with longitudinal slots and provided with studs bearing against the cams and with brake-shoes upon the long rearwardly-projecting arms supported by chains 55 from the body of the cam, and having springs forcing the shoes outward, transversely-journaled rock-shafts at the ends of the car having arms at the ends pivotally connected through rods to the upwardly-projecting arms of the 60 sleeves and having arms at the middles, longitudinally-sliding draw-bars having springs for drawing them in and having notches in their upper sides, and connecting rods pivoted to them and to the middle arms of the rock-shafts, dogs engaging the notches and having upwardly-projecting arms engaged by vertically-traveling slides in the dash-boards, horizontally-fulcrumed levers 37, bearing with lips 39 at their inner ends against the inner ends 65 of the draw-bars, and brake-shafts having handles and ratchets, and having chains and rods connecting them to the outer ends of the levers, as and for the purpose shown and set forth. 70

In testimony that I claim the foregoing as my own I have hereunto affixed my signature in presence of two witnesses.
